Primary Examiner—Gary D. Watson*Attorney, Agent, or Firm*—Litman, McMahon and Brown, L.L.C.[57] **CLAIM**

The ornamental design for a flexible spring hinge for chair back and seat, as shown and described.

DESCRIPTION

FIG. 1 is a rear, lower, perspective view of a flexible spring hinge for a chair back and seat, showing my new design; the broken lines indicating a chair are shown for illustrative purposes only and form no part of the claimed design; FIG. 2 is an enlarged, lower rear perspective view thereof; FIG. 3 is a bottom plan view thereof; FIG. 4 is a right side elevational view thereof, the left side being a mirror image thereof; FIG. 5 is a rear elevational view thereof; FIG. 6 is a front elevational view thereof; and, FIG. 7 is a top plan view thereof. FIGS. 3 through 7 have been shown on a reduced scale in respect to FIG. 2 but on an enlarged scale with respect to FIG. 1.
